CLAIM

The ornamental design for a tank, as shown and described.

DESCRIPTION

FIG. 1 is a front view of a tank showing my new design; FIG. 2 is a rear view thereof; FIG. 3 is a top view thereof; FIG. 4 is a bottom view thereof; FIG. 5 is a left side view thereof; FIG. 6 is a right side view thereof; FIG. 7 is a bottom perspective view thereof; FIG. 8 is a left side perspective view thereof; FIG. 9 is a right side perspective view thereof; FIG. 10 is a top exploded view thereof, showing the lid and the base of the tank being separated; and, FIG. 11 is a bottom exploded view thereof, showing the lid and the base of the tank being separated. The evenly spaced broken lines depict portions of the tank that form no part of the claimed design. The dot-dash-dot lines are shown for illustrative purposes only and form no part of the claimed design.
